TWO-CYCLE ENGINE

David Blumberg, Bridgeport, Conn.

Application August 20, 1943, Serial No. 499,315

4 Claims. (Cl. 123—51)

1

This invention relates to new and useful improvements in internal combustion engines and has particular relation to a two-cycle engine.

Among the objects of the invention are to provide in an engine of the type indicated means for thoroughly scavenging the engine cylinder of burned gases, means for forming a large explosive charge in the engine cylinder, an engine of simple construction involving but a relatively few parts, and an improved power take-off means for the engine whereby with a number of the engines operating in a bank any one or more may be stopped without imposing a heavy drag on the others.

Other objects and advantages will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a top plan view showing the engine of the invention;

Fig. 2 is a horizontal central sectional view through the engine;

Fig. 3 is a view with the engine casing in vertical section but with the piston structure in elevation;

Fig. 4 is a view partly in plan and partly in section and showing the piston construction and crank means alone;

Fig. 5 is a perspective view of one part of the crank means alone;

Fig. 6 is a quarter section view of the switch controlling energizing of the spark plug;

Figs. 7 through 11 are schematic views showing the various positions of the crank means;

Fig. 12 is a side elevational view of the engine cylinder alone;

Fig. 13 is an elevational view of the block used in mounting the crank means;

Fig. 14 is a similar view but taken at right angles to Fig. 13;

Fig. 15 is a detail elevational view looking at the underside of the engine cylinder as suggested by the line 15—15 of Fig. 12; and

Fig. 16 is a transverse sectional view taken as along the line 16—16 of Fig. 12.

Referring in detail to the drawings the engine of the invention is shown as including a one-piece casing or cylinder 10 open through both

2

ends and provided at spaced points with raised or radial flange-like portions 11, 12, 13, 14, 15 and 16 the purpose of which will appear. The respective ends of the cylinder 10 are closed by heads 17 and 18 bolted or otherwise secured in place. An intake port 19 is provided in head 17 and communicating with said port is a fuel supply pipe 20. A valve 21 controls the port 19 and at the proper times is maintained seated by a coil spring 22 disposed about the stem of the valve. Head 18 is provided with an intake port 23 with which communicates a fuel supply pipe 24. A valve 25 controls the port 23 and is adapted to be seated at the proper times by a coil spring 26 disposed about the stem of the valve.

Members 27 and 28 are disposed in spaced relation about the intermediate portion of the cylinder 10 and are secured against the opposing faces of the radial flanges 13 and 14 respectively.

The members may be in two or more pieces and are bolted, welded or otherwise formed into units and in any similar manner secured tight to said flanges. A water jacket 29 is secured in spaced relation to the main walls of the cylinder 10 by being secured to the flanges 11—12 and 15—16 as shown in Figs. 2 and 3. Water supply and return pipes 30 and 31 are shown as connected with the water jacket at the respective sides of the central or intermediate portion of the cylinder 10 (see Fig. 3).

At the underside of the engine an oil pan 32 may be bolted at 33 to the lower portions of the members 27 and 28 and at such side the members are provided with flanges 34 having holes 35 for the passage of anchoring bolts or the like to be used in securing the engine to any suitable base (not shown). A plate 36 is secured to and between the upper portions of the members 27 and 28 as by bolts 37 and such plate toward each side of the engine has a pin 38 passing therethrough. About each pin is a coil spring 39 bearing at its respective ends against a head 40 of the pin and a socket provided in the plate and receiving the inner end of the spring.

These pins enter into the starting of the engine as will later appear and the pins are normally held in elevated positions by the springs 39. The heads of the respective pins are engaged by rollers 41 on the respective arms 42 and 43 of a rocker device generally designated 44 (see Fig. 1) pivotally mounted on a bar 45 carried by bearing members or lugs 46 on the upper side of the plate 36. A manual means 47 is provided for pulling 55 to pivot the rocker 44 on bar 45 to depress the

pins 38 against the tendency of the coil springs 39.

Spark plugs 48 and 49 are threaded through thickened cylinder side wall portions 50 and 51 respectively and enter the cylinder toward but spaced from the heads 17 and 18. Firing of the plugs is controlled by similar switches 52 and 53 located at the ends of the cylinder and mounted by the heads 17 and 18. These switches are normally in open circuit relation and are closed by a firing chamber head as the latter reaches the end of its compression stroke.

Each switch (see Fig. 6) includes a threaded outer metal shell 54 adapted to be screwed into a tapped hole in the cylinder. Within said metal shell is a body 55 of insulating material mounting a pair of spaced contacts 56 and 57 connected by wires 58 and 59 with binding posts 60 and 61 respectively. Such posts are carried by the body 55 and exposed at the outer end of the metal shell 54. A lead 62 from a battery or the like (not shown) is connected with binding post 60 while a similar lead 63 connects the binding post 61 with the center electrode of a spark plug.

Located within the metal shell 54 beyond the inner end of the insulating body 55 is a contact or circuit closing means in the form of a head 64 normally held away from contacts 56 and 57 by a coil spring 66. A rod 67 projecting from said head 64 passes out through the shell wall 65 and may be provided with a small head 68 for engagement by a firing chamber head for the closing of the switch to energize a spark plug.

As shown best in Fig. 3 the rod 67 and its head 68 project slightly into the engine cylinder to be engaged by the mentioned firing chamber head at the time above indicated. When so engaged the rod and its head are pushed outwardly of the cylinder 10 and inwardly of the metal shell 54 and the head 64 is moved against the tendency of the coil spring 66 and into engagement with the contacts 56 and 57 closing the circuit through them and thus to a spark plug.

In its opposite sides the cylinder 10 is provided with longitudinally extending slots 69 in which operate portions of a crank mechanism. The crank mechanism or power take-off means comprises a pair of similar means generally designated 70 and 71 and of which the means 70 is shown alone in perspective in Fig. 5.

Such means includes a crank shaft 72 connected by a web 74 with a head, shown as a disc 75. Web 74 and crank 72 are at one side of the disc 75 and extending from the other side thereof in rigid concentric relation therewith is a drive shaft 76. Web 74 is pivotally connected with the disc 75 in eccentric relation thereto as at 77 and such pivotal connection is located intermediate the ends of the web. At its end remote from the crank 72 the web mounts a roller 78 the purpose of which will be set forth.

As suggested the crank mechanism is duplicated at each side of the cylinder 10 and it is operated or driven by a double piston construction located within the cylinder and generally designated 79. Such construction comprises a pair of piston heads 80 and 81 each in the form of an annulus and provided with a skirt portion designated 82 and 83, respectively, telescoping at their inner ends as at 84 and provided with side holes receiving the cranks 72. The telescoped portions of skirts 82 and 83 are rigidly connected.

Within said skirt portions and about the crank

arms 72 is a cylindrical bushing 85 received in an annular block 86 having an opening 87 therethrough for such bushing. Block 86 has flanges 88 which bear against the inner surfaces of the skirt of piston 81 as best shown in Figs. 2 and 4 and the block is movable as a unit with the pistons. A pair of holes 89 and 90 communicate the opening 87 through the block 86 with the interior of the piston skirts at the respective sides of the block. These openings pass not only through the block but also through the bushing 85.

Inner cylindrical liners 91 and 92 in the skirts 82 and 83 respectively, bear against the flanges 88 of the block 86 and such liners toward their outer ends are provided with holes 93 and 94, respectively. When the engine is assembled the free ends of the cranks 72 are in, or substantially in, abutting aligned relation as in Figs. 2 and 4 and through such cranks extends an opening 95. Such opening through radial openings 96 communicates with arcuate channels or grooves 97 in the surface portions of the cranks and which in certain positions are in communication with the respective openings 89 and 90 through the block 86 and bushing 85 entering the cylinder 10 at opposite sides of said block.

Outwardly of the respective pistons 80 and 81 are firing chamber heads 98 and 99. Rigid with the respective heads 98 and 99 are skirts 100 and 101 passing through the pistons 80 and 81, respectively, and engaged by packing or piston rings 102 as they so pass. At their inner ends the skirts 100 and 101 are provided with annular outwardly enlarged portions 103 and 104, respectively, carrying piston rings bearing on the inner surfaces of the skirt liners 91 and 92, respectively.

Within the skirts 100 and 101 are annular members 105 and 106, respectively, held against shoulders 107 of the skirts by bolts 108 whereby such members have a fixed relation to the heads 98 and 99, respectively, and are movable with such heads and their skirts. Members 105 and 106 are provided each with a valve seat for the valves 109 and 110 of the respective members and which valves are normally urged toward their seats by coil springs 111 disposed about the stems of the valves. Openings 112 communicate the space between the members 105 and 106 and the respective firing chamber heads and within the skirts 100 and 101 with the spaces 113 and 113a between the respective pairs of heads but at the outer sides of said skirts.

Through the firing head 98 are one or more passages 114 communicating the outer side of said head with the space 115 located centrally of the inner side of such head while a similar passage 116 provides communication between the outer side of the firing chamber head 99 and the space 117 at the inner side of such head. A valve including an inverted cup-like part 119 controls the passages 114 and a similar valve 120 controls the passages 116. These valves are normally held in positions closing the respective passages by coil springs 121 but are adapted to be forced off their seats by pressure to permit of the movement of fuel from the outer to the inner sides of the respective firing chamber heads.

Exhaust ports 122 and 123 in the respective end portions of cylinder 10 communicate with annular passages 124 and 125, respectively, formed by the cylinder flanges 12-13 and 14-15 and cover members 126. Suitable exhaust pipes 127 may be connected with the mentioned annular

passages and the number of exhaust ports entering such passages may be varied. When the engine is assembled the webs 74 of the crank mechanism are received in the members 27 and 28 at the sides of the cylinder 10 and the discs 75 are also located between such members. The shafts 76 are disposed in bearings 127 each mounted by an annulus 128 held in such members by bolts 129. Each annulus has a cover plate 130 bolted or otherwise secured thereto and maintaining the mentioned bearing means in place.

In its intermediate portion the bottom wall of the cylinder 10 is provided with a pair of spaced longitudinally extending slots 131 and 132. The spacing of these slots is the same as that of the entrance openings 133 and 134 in the bottom of the entrance openings 133 and 134 in the bottom of the block 86. Such entrance openings communicate with the respective sides of the block through passages 135 and 136 respectively. Clearly when the entrances 133 and 134 are in registry with their slots air passages are established from the exterior of cylinder 10 to the interiors of the skirts 100 and 101 of the firing chamber heads 98 and 99.

In the operation of the engine assuming the parts to be in the positions of Fig. 2 a firing stroke driving the piston construction 79 toward the right has just been completed. The burned gases have been exhausted and scavenged through the port 122, a new charge has been drawn in through the intake port in cylinder head 17, and a charge has been compressed in the space 113a between the piston 81 and the firing chamber head 99 and is ready to be ignited. Fig. 3 shows the piston construction at the end of its stroke following or resulting from the firing of the charge in the space 113a.

When the charge is ignited in the space 113a (which space is in the form of an annulus) the piston 81 is forced toward the left while the firing chamber head 99 together with its skirt 101 and member 106 remains stationary. This results in the compression of air in the annular space 137 between the liner 92 and the skirt 101 and, due to the presence of the hole 94, between the liner 92 and the skirt of piston 81. Further at this time air is admitted to the chamber 138 within the skirt 101 through the opening 95 in the crank 72, passage 96 and groove 97, passage 90 and also through slot 131, entrance 133 and passage 135.

There being two independent passages for the supply of air to the chamber 138 neither passage need be large and the rapid supply of the required supply of air is assured. As the block 86 nears the end of the piston stroke its entrance 133 moves off the end of slot 131 and no further supply of air is obtained from that source. In addition as the crank 72 turns its arcuate groove 97 is moved out of register with the passage 90 closing off the second source of supply of air to the chamber 138 and sealing the latter.

During movement of the piston in the direction indicated a plentiful supply of air is therefore trapped in the chamber 138. Now when the piston head 81 moves past the exhaust port 123 the pressure between said piston head and the firing head 99 drops. At such time the compressed air in the space 137 and in the space between the liner 92 and the skirt of the piston head 81 acts on the portion 104 of the skirt of the firing chamber head 99 and such skirt and head together with the member 106 are moved in the direction of the piston or away from the cylinder head 18.

This movement of firing chamber head 99 results in the intake valve 25 being drawn open or unseated against the tendency of its coil spring and fuel from the supply pipe 24 is drawn into the cylinder between the head 99 and the head 18. Valve 110 remains seated at this time as there is no pressure to force it inwardly from its seat and it is preferred that the same be held on its seat under a pressure of approximately two pounds.

As the firing chamber head 99 and its skirt and member 106 are drawn inwardly by the expansion of the compressed air in the chamber 137 the air in chamber 138 is slightly compressed and forces valve 110 from its seat. The air then escaping under the valve 110 serves to scavenge the burned gases from the engine and it is also noted that the downward or inwardly movement of the firing chamber head 99 in the manner described serves to move the burned gases toward the exhaust port 123. Thus a thorough scavenging of the engine is accomplished. Valve 110 is held on its seat with but a slight pressure, as, for example, two ounces so that the valve readily opens to permit of passage of air from chamber 138.

When the heads 81 and 99 were moving in the direction just described the head 80 with its skirt and the firing chamber head 98 and its skirt were being moved toward the left as viewed in Fig. 2. This is a compression stroke for the parts to the left of the cranks in Fig. 2 and the piston 80 and firing chamber head 98 move substantially as a unit since the inner ends of the skirt of each is 35 positively moved by the block 86.

In Fig. 2 it will be understood that the space 113 has been scavenged of burned gases and that a charge has been drawn into the space between the cylinder head 17 and the outer side of the firing chamber head 98. Thus the air pressure has been exhausted from the chamber 140 within the skirt 100 and the valve 109 closes. The air mentioned has been drawn into said chamber 140 through passages 95 and 96 and groove 97 and through slot 132, entrance 134 and passage 136 in the block 86 during the power stroke of piston 80. As the parts start to move the valve 119 remains closed during initial movement and until the piston 80 has moved sufficient to close the exhaust port 122.

Pressure builds up on the fuel charge in the space mentioned and forces open the valve 119 to expose the outer ends of the passages 114 so that the fuel charge moves through head 98 (valve 21 having now closed) and into the space between the piston 80 and the firing chamber head 98 and within the skirt 100 and above the member 105 from which space through openings 112 the fuel moves into the space 113. At the end of the stroke the piston construction has shifted to the extreme left of the cylinder 10 and a charge is ready to be fired at such end while a charge has been drawn into the right hand end of the cylinder and is ready to be compressed and forced into the space 113a between the piston 81 and the firing chamber head 99.

At this time the crank 72 is in the position reverse to that of Fig. 2 and is in the position of Fig. 3. That is, the cranks have moved from the right hand end to the left hand end of the slots 69. Small valves 142 in the walls of skirts 100 and 101 serve to prevent the creation of any vacuum in the chambers 137 and 143 between the skirt 101 and the skirt of piston 81 and the skirt 100 and the skirt of piston 80.

As the engine continues to operate the above described cycle of operation is repeated. Movement of the piston construction in one direction compresses a charge and forces it into the firing chamber at one end of the cylinder while a charge is fired, the burned gases scavenged, and a new charge drawn into the cylinder at the other end thereof. The cranks 72 are moved back and forth in the cylinder slots 69.

Attention is called to the fact that when the piston heads are moved to close the exhaust ports air is trapped between the piston heads and the firing chamber heads and this air is used as an addition to the charge drawn through the intake ports at the respective ends of the cylinder. Thus, while in each instance a large charge is drawn into the cylinder such charge is further increased in volume by the presence of the mentioned trapped air.

During reciprocation of the piston construction as described the cranks 72 are carried back and forth in the slots 69 of the cylinder 10. These cranks are located in eccentric relation to the heads or discs 75 and the shafts 76 and further the pivots 77 of the webs of the cranks are in eccentric relation to the discs and shafts. Thus looking at Fig. 7 the crank position is that of Fig. 2.

As the cylinder construction remains stationary and the piston construction moves toward the left from the position of Fig. 2 the pivot pins 77 of the crank webs move upwardly turning the discs 75 and the cranks move through the centers of the discs (Fig. 8) to the positions of Fig. 9. Then on the reverse stroke of the piston the webs and pivots move downwardly while the cranks move back through dead center as shown in Fig. 10 to the position of Fig. 11 which is the same as that of Fig. 7 the chosen starting position.

When the engine is stopped as by the closing of its fuel supply and the opening of its ignition circuit the piston construction comes to a dead center position bringing the cranks 72 into alignment with the shafts 76 and concentric with them and the discs 75. This is due to the fact that the pins 77 are located the same distance from the centers of cranks 72 as from the center of the shafts 76. Now if the pins 38 (Fig. 3) are in their upper positions, on any attempt to start the engine by a cranking action applied to either or both shafts 76 the latter with the discs 75 will merely spin around carrying the pins 77 but not moving the piston construction.

To start the engine the pins 38 are depressed by actuation of the rocker 44 so that such pins are against the rollers 78 of the respective crank webs 74. Now as the engine is cranked or a turning movement is applied to the shafts 76 the rollers 78 engaging the pins act through the crank webs and shift the cranks laterally moving them out of dead center position and shifting the piston construction. From there on the cranking of the engine proceeds in the usual manner. Since when the engine is stopped turning of the shafts

76 does not impart movement to the piston construction, but results merely in rotation of such shafts, the discs 75, webs 74 and cranks 72 it will be clear that in any arrangement involving a plurality of the engines in a line with their shafts 76 coupled any one or more of the engines may be stopped or may get out of order and stop without imposing a large burden on the yet operating engines of the bank.

Having thus set forth the nature of my invention, what I claim is:

1. In a two cycle internal combustion engine, a cylinder and piston construction, a crank means, said crank means including a crank connected with said piston construction for reciprocation thereby, a web connected at one end with said crank, a power take-off shaft, a head on said shaft, a pivot connecting said web with said head, and said pivot eccentric to said crank and said shaft and equally spaced from each of them whereby said crank is in alignment with said power take-off shaft when said piston construction is in a dead center position.

2. In a two cycle internal combustion engine, a cylinder, a double ended piston construction in said cylinder, a crank means including a crank connected with said piston construction for reciprocation thereby, a web connected at one end with said crank, a power take-off shaft, a head on said shaft, a pivot connecting said web with said head, and said pivot eccentric with said crank and power take-off shaft and equally spaced from each of them whereby said crank is in alignment with said power take-off shaft when said piston construction is in a dead-center position.

3. In a two cycle internal combustion engine, a cylinder, a double ended piston construction in said cylinder, a crank means including a crank connected with said piston construction for reciprocation thereby, a web connected at one end with said crank, a power take-off shaft, a head on said shaft, a pivot connecting said web with said head, said pivot eccentric with said crank and power take-off shaft and equally spaced from them whereby said crank is in alignment with said power take-off shaft when said piston construction is in a dead-center position.

4. In a two cycle internal combustion engine, a cylinder, a double ended piston construction in said cylinder, a crank means including a crank connected with said piston construction for reciprocation thereby, a web connected at one end with said crank, a power take-off shaft, a head on said shaft, a pivot connecting said web with said head, said pivot eccentric with said crank and power take-off shaft and equally spaced from them whereby said crank is in alignment with said power take-off shaft when said piston construction is in a dead-center position, and manually controlled means for moving said piston construction out of dead-center position to disalign said crank and said power take-off shaft to enable cranking of the engine to be accomplished by turning of said shaft.

5. In an engine, a cylinder and piston construction, a crank connected with said piston construction for reciprocation thereby, a web connected with said crank, a power take-off shaft, a head on said shaft, a pivot connecting said web with said head, and said pivot eccentric with said shaft and crank and equally spaced from each of them whereby said crank is aligned with said shaft when said piston construction is in a dead-center position and said shaft may be rotated without movement of the piston construction.

DAVID BLUMBERG.
